MILK BOTTLE CRATE

Houston Rehrig, Pasadena, and Richard F. Gildart, Montebello, Calif., assignors to Rehrig Pacific Company, Los Angeles, Calif., a corporation of California

Filed Sept. 1, 1966, Ser. No. 3,689

Term of patent 14 years

(Cl. D58—5)

FIG. 1

FIG. 2

FIG. 1 is a front perspective view of a milk bottle crate showing our new design;

FIG. 2 is a side elevation thereof on an enlarged scale, the other sides being identical thereto and the bottom being of a conventional configuration.

The dominant features of the design reside in the full line portions of the drawing.

We claim:

The ornamental design for a milk bottle crate, substantially as shown and described.
